UNITED STATES PATENT OFFICE.

BENJAMIN F. MAYO, OF SALEM, MASSACHUSETTS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

HEELING-MACHINE.

1,301,899.

Specification of Letters Patent. Patented Apr. 29, 1919.

Application filed July 30, 1917. Serial No. 183,488.

To all whom it may concern:

Be it known that I, BENJAMIN F. MAYO, a citizen of the United States, residing at Salem, in the county of Essex and State of Massachusetts, have invented certain Improvements in Heeling-Machines, of which the following description, in connection with the accompanying drawings, is a specification, like reference characters on the drawings indicating like parts in the several figures.

This invention relates to heeling machines, and more particularly to that type of heeling machine in which provision is made for measuring the thickness of the work preliminarily to the application of the final pressure and the driving of the nails.

In machines of the type referred to, it is customary to lock the measuring mechanism after its operation, in order to prevent it from slipping under the stress of the very heavy, final pressure to which the work is subjected before and during the nail driving operation.

The object of the present invention is to provide improved means for unlocking the measuring mechanism at the completion of the heel attaching operation and preparatory to the resetting of the said mechanism for the next operation of the machine.

The invention is herein illustrated and described as embodied in a heeling machine of the type shown in an application of John M. Benjamin, Serial No. 183,314 filed July 28, 1917, to which reference may be had for a complete disclosure of a heeling machine to which my invention is applicable.

In the machine disclosed in the application above referred to, frictional means is provided for locking the measuring mechanism against slipping at the time when it has to support the final pressure and a feature of the present invention resides in the provision of means for partly or wholly disengaging the coöperating friction surfaces in order to permit the measuring mechanism to be easily reset after the locking device has performed its function.

In a preferred form of the invention the measuring mechanism may include a rotatable screw and the locking means may conveniently consist of coöperating conical

locking members, one of which moves with the screw and the other of which is held against movement, means being provided for disengaging the conical members from each other by relative axial movement. In the practical form of the machine herein illustrated, one of the conical locking members is mounted upon the measuring screw and means, controlled by the crank shaft of the machine, is provided for effecting axial movement of the screw and the conical locking member upon it, to disengage it from the co-operating stationary locking member, in order to permit free action of the screw when it is to be reset.

Other features and advantages, more or less specific, incident to and resulting from the use of the invention, will be apparent from a reading of the following specification in connection with the accompanying drawings, and the scope of the invention will be defined in the appended claims.

In the drawings,—

Figure 1 is a view, partly in section and partly in elevation, showing the measuring and final pressure mechanisms of a heeling machine and a form of unlocking mechanism embodying the present invention; and

Fig. 2 is a perspective view showing, upon an enlarged scale, a detail of the unlocking mechanism.

The numeral 10 indicates the base or frame of the heeling machine. The usual reciprocating driver carrying spindle is indicated at 12. The spindle 12 is actuated by a toggle 14, operated, through a connecting rod 16, from a crank 18, as is usual in machines of this type.

A back rod 20, at the rear of the machine, transmits the measuring movement to the work and the amount of measuring movement is controlled by an adjustable stop 22.

The measuring operation is accomplished primarily by a screw 24 which, when it is rotated, produces longitudinal movement of a non-rotatable nut 26 connected to the back rod 20 by a toggle link 28. After the measuring is accomplished, the final pressure is applied to the work by straightening the toggle comprising the link 28 and the back rod 20. This is effected by straighten-

ing a toggle, consisting of links 30, 32, by power derived from the connecting rod 16 and transmitted through a link 34. The screw 24 is provided with an enlarged conical portion 36 and a coöperating, correspondingly formed, conical seat is provided in the stationary bracket 38 secured to the frame 10. Below the cone 36 a pinion 40 is formed upon the stem of the screw 24 and a rack 42, meshing with the pinion, is guided in suitable ways in the bracket 38 for reciprocation forwardly and rearwardly of the machine. A heavy spring 44, connected at its rear end to the rack 42 and at its front end to the machine frame, provides the necessary force for drawing the rack forwardly to effect the measuring operation. When the machine is at rest, the spring 44 is held under tension, ready to perform its measuring function, by the engagement of a dog 46, upon the rack 42, with a hook 48 controlled by the connecting rod 16.

When it is desired to measure the work, a plunger 50 is operated to release the dog 25 from the hook 48, permitting the spring 44, through the rack 42, to rotate the measuring screw and elevate the nut 26. As the measuring pressure is applied to the work the cone 36 is, by reaction, forced more and more 30 tightly into its seat and when the measuring operation is completed the frictional engagement between the two conical surfaces effectually locks the measuring screw against rotation under the stress of the subsequently 35 applied, heavy, final pressure.

The mechanism thus far described is disclosed and claimed in the Benjamin application, previously referred to, and is described here merely for the purpose of illustrating 40 the application of my invention.

After the release of the final pressure, the measuring screw 24 must be rotated in a reverse direction in order to retract the back rod 20 and reset the machine for the next 45 operation. When the cone 36 is very tightly seated in the member 38 an excessive amount of power may be required to dislodge it preparatory to its reverse rotation. By the present invention, however, I have provided 50 means for preliminarily disengaging the cone, more or less, from its seat in order to permit reverse rotation of the measuring screw without undue waste of power.

Referring to Fig. 1, a plug 52, having a 55 hemispherical cavity, is inserted in the lower end of the stem of the measuring screw and one end of a pin 54, having hemispherical ends, is seated in the cavity. The other end of the pin is seated in a similar hemispherical cavity in a plug 56 mounted in a cam lever 58 which is pivoted in the frame 10 at 60. The plug 56 is seated upon a screw 62, threaded into the cam lever, to provide for adjustment of the plug.

65 Projecting rearwardly from the cam lever

58 is a pin 64 to the outer end of which is attached one end of a tension spring 66. The other end of the spring is anchored to a stationary pin 68. The purpose of the spring is to hold a cam roll 70, mounted in the inner end of the cam lever 58, in engagement 70 with a cam 72 rigidly mounted upon the crank shaft of the machine. When the machine is at rest, and during the measuring, the final pressure, and nail driving, the cam 75 does not operate upon the cam roll 70; but immediately after the release of the final pressure, the cam depresses the cam roll and, consequently, raises the pin 54 and the measuring screw, moving the cone 36 axially 80 until it is disengaged from its seat in the member 38. The measuring screw is now free to rotate and is automatically reset prior to the stopping of the machine.

The machine stops with the crank 18 and 85 the cam 72 in approximately the position shown in Fig. 1, the cam roll 70 having dropped off the high part of the cam after the measuring mechanism is reset. The longitudinal position of the measuring screw 90 and the cone 36 is thus no longer controlled by the cam 72 and the cone is free to seat itself and lock the screw again at the conclusion of the next measuring operation.

The screw 62 permits such adjustment of 95 the measuring screw relatively to the unlocking mechanism as to allow the cone 36 to be seated properly and to be disengaged at the proper time in the operation of the machine.

Having described my invention, what I 100 claim as new and desire to secure by Letters Patent of the United States is:—

1. In a machine of the class described, the combination of a measuring screw, means for rotating the screw to effect a measuring operation, means provided with coöperating friction surfaces for locking the screw to a stationary part of the machine, and means for disengaging said surfaces to permit free action of the screw. 105

2. In a heeling machine, the combination of a measuring screw, frictional means for locking the screw to a stationary part of the machine, and means for releasing the screw.

3. In a heeling machine, the combination 115 of a measuring screw, means for rotating the screw to effect a measuring operation, a conical locking member upon the screw, a coöperating stationary locking member, and means for disengaging said locking members 120 to permit free action of the screw.

4. In a heeling machine, the combination 125 of a work support, a measuring screw, means for rotating the screw to move the work support, a conical locking member connected to rotate with the screw, a coöperating stationary conical locking member, and means for effecting relative axial movement of said locking members to disengage them and permit free action of the screw. 130

5. In a heeling machine, the combination of a work support, a measuring screw, connections between the measuring screw and work support, means for rotating the screw to move the work support, a conical locking member upon the screw, a coöperating stationary conical locking member, and means for effecting axial movement of the first-mentioned locking member to disengage it from the stationary locking member and permit free action of the screw. 10

In testimony whereof I have signed my name to this specification.

BENJAMIN F. MAYO.
